UNITED STATES PATENT OFFICE

2,110,814

ROLL WRAPPING MACHINE

Philip D. Parsons, Swarthmore, Pa., assignor to
Scott Paper Company, Chester, Pa., a corpora-
tion of Pennsylvania

Application March 20, 1935, Serial No. 12,075

12 Claims. (Cl. 93—2)

This invention relates primarily to improvements in machines for wrapping toilet paper and like rolls.

In United States Patent No. 2,005,846 I have disclosed a machine for applying wrappers to rolls without the use of "pick-up" glue applied to the roll itself, and the principal object of the present invention is to provide as an adjunct of this machine improved mechanism for neatly and securely folding the applied wrappers against the ends of the roll, and to subsequently apply to the folded ends of the wrappers gummed labels for retaining the folds in position and for providing a substantially air-sealed package.

15 The mechanism forming the subject of the present invention is illustrated in the attached drawings, in which:

Figure 1 is a side elevational view of a machine made in accordance with my invention;

20 Fig. 2 is a transverse sectional view on the line 2—2, Fig. 1;

Fig. 3 is a diagrammatic showing of a portion of the mechanism;

25 Fig. 4 is an end elevation and partial sectional view on the line 4—4, Fig. 2;

Fig. 5 is a longitudinal sectional view on the line 5—5, Fig. 2;

30 Fig. 6 is an enlarged fragmentary partial sectional view illustrating a detail of the mechanism;

Fig. 7 is an enlarged sectional view through one of the forming heads.

Fig. 8 is a view similar to Fig. 7 illustrating the elements of one of the forming heads in another position of adjustment;

35 Fig. 9 is a face view of one of the forming heads as viewed from the line 9—9, Fig. 8;

Fig. 10 is a transverse sectional view on the line 10—10, Fig. 8;

40 Fig. 11 is an enlarged fragmentary sectional view illustrating details of the folding heads;

Fig. 12 is a view similar to Fig. 11 showing the elements in another position of adjustment;

45 Fig. 13 is a view in perspective of an element of the folding head;

Fig. 14 is a longitudinal section on the line 14—14, Fig. 2;

Fig. 15 is an enlarged fragmentary view showing a detail of the label-applying mechanism;

50 Fig. 16 is a sectional view on the line 16—16

Fig. 15;

Fig. 17 is a fragmentary end elevational view of a portion of the mechanism shown in Fig. 14;

55 Fig. 18 is a front elevational view of the mechanism shown in Fig. 17;

Fig. 19 is an end elevation and partial sectional view of the label-feeding mechanism;

Fig. 20 is a longitudinal sectional view on the line 20—20, Fig. 19;

Fig. 20a is a face view of one of the elements 5 shown in Fig. 20;

Fig. 21 is a transverse sectional view on the line 21—21, Fig. 1;

Fig. 22 is a diagrammatic view showing a detail 10 of the drive mechanism;

Fig. 23 is a section on the line 23—23, Fig. 21;

Fig. 24 is a sectional view on the line 24, 24, Fig. 23;

Fig. 25 is a fragmentary view showing a detail 15 of the mechanism illustrated in Fig. 23;

Figs. 26 to 31, inclusive, are diagrammatic views illustrating the mode of operation and relation between the various parts of the machine during a complete cycle of operations;

Figs. 26a to 31a, inclusive, illustrate the roll 20 package in the various progressive stages corresponding to the operations illustrated in Figs. 26 to 31, inclusive, and

Fig. 32 is a graphic illustration of the various 25 movements of the mechanism.

The function and various operations of the machine will be more readily understood by reference first to Figs. 5, 26a to 28a, inclusive, and 31a. The rolls 1 are fed to the machine on an endless conveyer 2, said rolls before being deposited upon the conveyer having had applied thereto by mechanism for example disclosed in my pending application Serial Number 711,744,

a wrapper 3, which as shown in Fig. 26a embraces the cylindrical roll and projects to a predetermined extent beyond the flat end faces of the latter. The conveyer 2 in its forward movement presents the partially wrapped rolls to gripping elements hereinafter described in detail carried by a rotary head 4 which moves in synchronism 30 with the conveyer 2, and on this head 4 the rolls are carried progressively through a series of operations which complete the package.

In the first of these operations as shown at 35 "A" in Fig. 5, the projecting ends of the wrapper 3 are turned inwardly against the flat ends of the roll 1 in such manner, see Fig. 27a, as to produce a series of outwardly projecting radial tucks 5, these tucks being uniformly distributed around the axis of the roll.

In the next operation and as shown at "B", Fig. 5, the tucks are folded in uniformly overlapped relation against the end surface of the roll, see also Fig. 28a.

In a subsequent operation as shown at "C" 40

Fig. 5, the tucks are turned inwardly against the end surface of the roll, see also Fig. 29a.

In a subsequent operation as shown at "D" 45

Fig. 5, the tucks are turned inwardly against the end surface of the roll, see also Fig. 30a.

In a subsequent operation as shown at "E" 50

Fig. 5, the tucks are turned inwardly against the end surface of the roll, see also Fig. 31a.

In a subsequent operation as shown at "F" 55

in Fig. 5 and in Fig. 31a, a label 6 of suitable size and form is adhesively secured to the ends of the package, said labels overlying the flattened tucks 5 and forming with the wrapper 3 a substantially sealed envelope for the roll.

Subsequent to this operation and as illustrated at "D", Fig. 5, the completed package is discharged from the rotary head 4 into a receiving chute 7.

10 As shown in Figs. 1, 2 and 3, power is applied to the rotary head 4 through a shaft 8, this shaft being connected to a vertical stub shaft 9 through bevel gears 11 and 12. The vertical shaft 9 is connected in turn to a horizontal stub shaft 13 through bevel gears 14 and 15, and the shaft 13 carries a spur gear 16 which meshes with a gear 17 carried by the main shaft 18 of the rotary head 4. As illustrated in Fig. 2, the rotor 4 comprises an intermediate section 19 which carries the 15 gripping devices, previously referred to, which remove the partially wrapped rolls from the conveyer 2, and these gripping devices in the present instance are six in number, see Fig. 5, and are uniformly distributed around the circumference of the intermediate section 19. The rotary head 4 also comprises two side sections 21 and 22, see Fig. 2, each of which carries a plurality of 20 gripping heads 23 which correspond in number to the said gripping devices and are located respectively in alignment with the latter.

Each of said gripping devices comprises a pair of curved fingers 24, 24, see Fig. 5, which are carried respectively by cylindrical hubs 25, 25 journaled between the side plates of the intermediate section 19 of the rotary head 4. The manner in which the arms 24 are connected to their respective hubs is best illustrated in Fig. 6. As therein illustrated, the fingers are journaled upon pins 24a, and each has attached to the outer face thereof a stud 24b which passes through an aperture in a hub extension 24c and carries at its outer end nuts 24d which limit the movement of the finger 24 with respect to the hub. A spring 24e is mounted on the stud 24b and is confined between the inner side of the hub extension 24c and the outer face of the finger 24 and tends to hold the finger in an advanced position with respect to the said hub extension. Intermediate the hubs 25 is a curved shoe 26 supported at the outer end of a stud 27 slidably supported in a bracket 28 secured to the inner face of one of said side plates. A spring 29 confined between the bracket 28 and the shoe 26 tends to hold the stud 27 in an advanced position.

55 From each of the hubs 25 a link 31 extends inwardly of the rotary head to a cross head 32 slidably mounted in a radial guide 33 in the intermediate section 19. This cross head is also connected through an adjustable rod 34 with an arm 60 35 secured to a shaft 36 journaled in the head and extending axially of the latter through the head section 21, see Fig. 2. To the fixed structure of the machine is mounted a cam 37 having a groove 38 which receives a roller 39 carried on the outer end of an arm 41 secured to the shaft 36, the shape of the said groove 38 being shown in dotted lines in Fig. 5. As the partially wrapped roll carried by the conveyer 2 approaches the synchronously moving head 4 and as shown in 65 Fig. 5, it is brought into position between the arms 24, 24, which as shown at the lower left of Fig. 5 are at this point in an extended position. As the movement progresses, the roll is brought into contact with the shoe 26, and the arms 24, 24 70 75 are brought together by the action of the cam 37

so as to substantially embrace the roll, and with the spring-pressed shoe 26 to firmly hold the roll in the intermediate section 19 of the head 4 between the adjacent sections 21 and 22 and in alignment with the forming heads 23, 23.

It will be noted by reference to Fig. 2 that the conveyer 2 comprises transversely spaced roll-supporting arms 42, 42, between which the arms 24, 24 of the roll-gripping devices of the rotary head may close upon the roll. When the roll has progressed on the rotary head 4 to the position "D", Fig. 5, the cam 37 acts to again spread and retract the arms 24, 24 from the sides of the roll, thereby permitting the latter to fall away from the head into the chute 7.

The forming heads 23 of the rotary head 4 constitute the means for folding the projecting ends of the wrapper 3 in the manner previously described and illustrated in Figs. 27a and 28a. The mechanism of the forming heads is illustrated in Figs. 7 to 13, inclusive. As therein illustrated, each head comprises a cylindrical casing 43, the open end of which adjoins the intermediate section 19 of the rotary head, while the outer end is closed by an end plate 44. Mounted within the head for both axial and rotational movement is a cylindrical sleeve 45, the normal position of which within the head is shown in Fig. 7 and which is adapted to be advanced or projected through the open end of the casing 43 by means hereinafter set forth to a position as shown in Fig. 8, in which a shoulder 46 on the sleeve engages a stop flange 47 at the open end of the casing 43. The sleeve 45 has in the interior thereof a series of axial guideways or slots 48 in which are slidably mounted a corresponding number of racks 49. Each of these racks is secured to a projecting arm of a spider 51 which project from a hollow cylindrical member 52, this member having at its outer end an extension 53 which receives a collar 54, and this collar is held in place upon the extension 53 by means of nuts 55 on the threaded extremity of the said extension 53. The collar 54, see Fig. 10, has trunnions 56 which enter slots in the bifurcations 57, 57 of an arm 58 of a bell crank lever 59, this lever being pivotally mounted at 61 in the section 21 or 22 of the rotary head 4 to which the associated forming head is attached. The other arm 62 of the bell crank lever 59 is loosely clamped in a block 63 mounted for sliding movement in guides 64 in the associated rotary head section 21 or 22, as the case may be, and the block 63 carries a cam roller 65 which enters a cam groove 66 in the cam 37, or in the case of those of the bell crank levers associated with the section 22 of the rotary head 4 in a cam groove 67 of a corresponding cam 68 secured to the fixed framework of the machine, as shown in Fig. 2. Through the medium of the cam groove, 66 or 67 as the case 60 may be, the bell crank lever is actuated to operate the member 52 between the positions in which this member is shown in Figs. 7 and 8, thereby correspondingly moving the racks 49.

Slidably mounted in the interior of the member 52 is a member 69 having a projecting flange 71 to which are secured in circumferentially spaced relation a series of brackets 72. The brackets 72 correspond in number to the racks 49 and are located adjacent to the respective racks. Each bracket carries a segmental pinion 73 which meshes with the associated rack 49 and which meshes also with a second segmental pinion 74 journaled on the bracket 72. As shown in Figs. 11, 12 and 13, each of the pinions 74 has 75

an extension 75 to which is pivotally attached at 76 a segmental shoe 77. The pinion 74 is recessed, as shown at 70, Figs. 11 and 12, for reception of a spring 78 which bears against the inner face of the segmental shoe 77 and tends to hold the outer end of the shoe away from the gear. At its inner end, the shoe 77 carries a pin 79 which in a given relative adjustment of the pinions 73 and 74 corresponding to the completely retracted position of the rack 49, see Figs. 7 and 11, engages the pinion 73 to force the outer end of the shoe in opposition to the spring 78 against the adjoining face of the pinion 74. It will be apparent that as the rack 49 is advanced toward the open end of the casing 43, the pinion 73 will act to rotate the pinion 74, as indicated by the arrows in Fig. 12, to thereby swing the segmental shoe 77 through the position shown in broken lines in Fig. 12 to a radial position with respect to the axis of the forming head 48, as shown in Figs. 8 and 9.

It will further be noted by reference to Fig. 9 that the segmental shoes 77 are so formed and relatively positioned that when in the aforesaid radial position, the edges of the adjoining shoes are spaced slightly from each other to provide therebetween narrow radial spaces, the function of which will be hereinafter set forth.

With reference again to Fig. 7, it will be noted that the outer end of the member 69 is countersunk and internally threaded for reception of the externally threaded end portion of a sleeve 81, the inner reduced end of which fits slidably in the bore of the reduced extension 53 of the member 52. This sleeve 81 forms a support for a spring 82 which is confined between the member 52 and the threaded end portion of the sleeve 81, which, as previously set forth, is secured to the member 69. This spring 82 tends to maintain the members 52 and 69 in the relative positions in which they are shown in Fig. 7. When, therefore, the member 52 is advanced from the retracted position shown in Fig. 7 through the medium of the bell crank lever 59 and as previously described, the spring 82 will act upon the member 69 to cause a corresponding advance movement of the latter. Since the brackets 72 secured to the member 69 bear at their forward ends upon a flange 83 secured to the outer end of the sleeve 45, this advance movement of the member 69 will also effect a corresponding advance movement of the sleeve 45. This unitary movement of the parts continues until the shoulder 46 engages the stop flange 41 of the casing 43, whereupon forward movement of the sleeve 45 is arrested, as also will be the forward movement of the member 69. The continued forward movement of the member 52 permitted by compression of the spring 82 now results in an advance movement of the racks 49 with respect to the member 69 and a consequent actuation of the pinions 73 and 74, resulting in adjustment of the segmental shoes 77 from their normal retracted positions, as shown in Fig. 11, to the extended or radial positions shown in Figs. 8 and 9.

In the operation, insofar as described, of this portion of the mechanism upon the partially wrapped package, the forming head in its relation to the package before the start of the operation is shown in Fig. 7. As previously described, the entire mechanism of the forming head is advanced in the initial movement to the position illustrated in Fig. 11, in which the projecting ends of the wrappers 3 are embraced by the

retracted segmental shoes 77. In the continued operation, the shoes are then extended toward their radial positions, the initial movement of the shoes in this direction being illustrated in Fig. 12, it being noted that the outer end or heel of the shoe is caused to resiliently engage the edge of the roll proper by the spring 78, while the shoe is swung downwardly through the position shown in dotted lines toward the radial fully extended position shown in Fig. 9. Fig. 8 shows the shoes in the fully extended positions in which they bear against the end surface of the roll, the wrapper thereby being formed with the projecting tucks, as shown in Fig. 27a, the tucks being formed by the paper projecting through the radial spaces between the edges of the adjoining shoes 77.

In order to lay the tucks 5 against the end face of the roll, as shown in Fig. 28a, it is now necessary, as indicated in the view of Fig. 8, to rotate the shoe assembly with respect to the roll. This is accomplished by cam mechanism illustrated in Figs. 7, 8 and 10. As therein illustrated, the member 45 has attached thereto at a point adjacent its inner end an inwardly projecting arcuate plate 84. This plate has bosses 85 apertured for reception of rods 86 which project into the interior of the casing 43 from an annular disk 87 slidably held and guided for rotational movement in a recess in the inner face of the end plate 44. The end plate, see Fig. 4, is provided with a concentric slot 44a through which connection is established between the disk 87 and one end of an arm 88, the other end of which is pivotally secured at 89 to one end of a lever 91 pivotally secured to the end plate 44. The other end of the lever 91 carries a roller 92 which engages in a cam 93 in a cam plate 84 secured to the fixed structure of the machine. The head 4 rotates the cam 93 at the appropriate point in the progressive movement of the forming head and effects a partial rotation through the rods 86 of the sleeve 45 and a corresponding rotative movement of the associated elements of the forming head, this rotative movement of the segmental shoes 77 having the effect, as previously described, of laying down the tucks 5 in a position flat against the ends of the roll, as shown in Fig. 28a.

In order to insure retention of the flat tucks 5 or folds in position preparatory to application of the labels 6, each of the forming heads is provided with a plunger 95 which extends through the end plate 44 and is guided in a bushing 96 set in the sleeve 81. A spring 97 tends to hold the plunger in a retracted position, as shown in Fig. 7, which position is determined by a collar 98 on the plunger stem which engages the end plate 44 as shown. The plunger is advanced as the head rotates by a cam 99, see Figs. 1, 2 and 27 to 29, 28a and 29a, supported on the fixed structure of the machine in the path of the outer end of the plunger, the operation being timed with relation to the action of the forming head 4 so that the inner end of the plunger engages the tucks at the end of the roll immediately after the latter have been laid flat, as previously described. The plungers remain in the advanced tuck-retaining position until the subsequent operation of applying the labels 6 requires their retraction, which is effected by release of the plunger from the cam 99 and the action of the spring 97. It will be noted by reference to Fig. 29 that the plungers 95 remain in the advanced

position after retraction of the forming elements into the forming head.

The labels 6 for the opposite ends of the rolls are carried respectively in two hoppers 101, 101, see Figs. 1 and 19, which are journaled at their upper ends between brackets 102, 102 constituting elements of the fixed framework of the machine, the depending open ends of the hopper being adapted to oscillate for a purpose herein-
5 after set forth. Positioned below each of the hoppers 101 and operatively associated therewith is a suction head 103 having at its periphery a perforated suction plate 104 which as the head 103 rotates is adapted to register with the
10 bottom open end of the hopper, as shown in Figs. 19 and 20. The suction head 103 is mounted upon a shaft 105 which is journaled in the framework of the machine, as shown in Fig. 20, and which is rotated from a bevel gear 106 which
15 meshes with a bevel pinion 107 carried by said shaft. Each of the hoppers 101 is oscillated in synchronism with the rotation of the associated suction head 103 by means of an arm 108 connected to its journal, to which arm is connected
20 a rod 109 which extends downwardly and has at its lower end a bifurcated member 111 embracing the shaft 105 and slidably engaged in slots in the opposite sides of a block 112 loosely mounted on the shaft. The member 111, see Fig.
25 10, carries a cam roller 113 which engages in a cam slot 114 in a cam plate 115 carried by the suction head 103. As the head is rotated, the cam functions to reciprocate the rod 109 and thereby to oscillate the arm 108 and the hopper
30 101. The cooperative relation between the suction head 103 and the hopper 101 is illustrated in Fig. 19, which at the left shows one of the suction heads at the point of initial engagement with the under side of the hopper. As the head
35 10 continues to rotate in the direction indicated, the hopper is oscillated to the right so that the suction plate 104 is brought by rolling action against the lowermost label in the hopper so that the latter is stripped from the hopper and caused to
40 15 adhere to the plate 104 by suction applied to the inner face of the plate, as hereinafter described.

As shown in Fig. 19, the suction head is provided with a channel 116 which extends from the under side of the perforated plate 104 to an
45 50 annular chamber 117 embracing the hub of the suction head 103. Said hub is also provided with ports 118 which establish communication between the chamber 117 and a longitudinal channel 119 in the shaft 105. The channel 119 extends to the end of the shaft 105, at which end the shaft carries a cupped member 121 which cooperates with a reversely positioned member 122 and a suitable gasket or bearing plate 123 to form a substantially sealed chamber with which the channel 119 communicates. The plate 123 is apertured at 120 so that communication may be established between the channel 119 and a channel 124 extending through the hub portion
55 60 of the member 122. This member has a splined connection with the fixed casing 125 so that it is held against rotation but may be forced axially by a spring 126 against the bearing plate or gasket 123. From the outer end of the channel 124 a suitable duct 127 extends to a suitable source of vacuum. The member 122, as shown in Fig. 20, has in its inner face a segmental groove 128a connected through a radial channel with the channel 124, and the groove 128a registers
65 70 75 intermittently with the aperture 120, giving an

intermittent application of suction to the plate 104.

As shown in Fig. 19, the suction heads 103 lie respectively at opposite sides of a rotary suction drum 128, this drum being shown in trans-
5 10 15 verse section in Fig. 21. This drum receives its rotation from a shaft 129 journaled in the fixed framework of the machine and upon which the drum is mounted. At opposite sides of the drum, this shaft carries the bevel gears 106, 106, which as previously set forth mesh with the bevel pinions 107 on the shafts 105 of the suction heads 103.

As shown in Fig. 22, the shaft 129 is extended at one end and is connected through bevel pinions 131 with a vertical shaft 132, which in turn is connected through a bevel gear 133 and a bevel pinion 134 with a shaft 135, which as shown in Fig. 1 carries a bevel pinion 136 which meshes with the bevel gear 12, this latter gear as previously set forth being connected through the pinion 11 with the power shaft 8.

As shown in Figs. 4, 21 and 23, the drum 128 has two double-ended suction heads 137 extending transversely of the drum and each presenting a perforated suction plate 138 to both of the rotary suction heads 103. Each of the suction heads 137 is connected through a valve 139 and a duct 141 to a channelled sleeve 142 secured on the hub of the drum 128. The sleeve 142 has 30 formed therein ports 143 communicating respectively with the ducts 141 and also with an annular chamber 144 in a sleeve 145, this sleeve being mounted upon the hub of the sleeve 142, see Fig. 21, but being prevented from rotating 35 with the sleeve by a pin 146 which engages an adjustable stop 147 on the framework of the machine. A spring 148 holds the sleeve 145 firmly against the ported face of the sleeve 142 and creates a substantially solid joint between the 40 ports 143 and the annular chamber 144. A suitable duct 149 extends from the sleeve 145 in communication with the chamber 144 to a suitable source of suction (not shown).

Each of the valves 139 comprises a valve element (not shown) which is normally held to its seat by spring pressure, and the valve element is opened by pressure of a lever 151 which bears against the projecting end of the valve stem 152, see Fig. 24. The lever 151 is pivotally mounted 50 on a bracket 153 secured to the drum 128, as shown in Figs. 23 and 24, and comprises a pin 154 which is guided in a block 155 pivotally mounted on the drum, said pin constituting a retainer for a spring 156 which exerts pressure on the lever 55 151 and through the lever upon the valve stem 152 to retain the valve open. The lever 151 also carries a roller 157 which by engagement with a cam 158 secured to the fixed structure of the machine, as shown in Fig. 1, effects a rocking of 60 the lever 151 to a position shown in Fig. 25, wherein the lever is retracted against the pressure of the spring 156 from the valve stem 152 to permit the valve 139 to close. The lever 151 also carries a pivotally mounted shoe 159 which 65 in the normal position of the lever 151 and as shown in Fig. 24 constitutes a bearing for the free end of a lever 161, this lever 161 being secured to a pin 162 journaled on the drum 128. A spring 163 confined between the lever 161 and an 70 arm 164 resiliently holds the lever 161 against the shoe 159. Also secured to the pin 162 is an arm 165 which carries at its outer end a roller 166, this roller being adapted to engage a cam 167 secured to the fixed structure of the machine, as 75

shown in Fig. 1. When as previously described, the lever 151 is retracted by the cam 158, the shoe 159 moves to a position clearing the normally contacting face of the lever 161, so that this lever takes a position under the pressure of the spring 163, as shown in Fig. 25, in which it functions by engagement with the shoe 159 to retain the lever 151 in the retracted position against the pressure of the spring 156. The cam 167 functions with the collar 166 to retract the lever 161 to release the shoe 159 and to thereby permit the lever 151 under action of the spring 156 to return to its original normal position bearing upon the valve stem 152 and opening the valve. It will be apparent that during the time that the lever 151 is held in the retracted position, the valve 139 will be closed whereby the suction heads 137 will be disconnected from the source of suction. The operation of this portion of the mechanism is as follows: The drum 128 is rotated in synchronism with the rotation of the suction heads 103, and the relative arrangement is such that the suction plates 104 of the heads 103 will register with the suction plates 138 of the drum 128. When fully registered with the plate 138, the suction on the plate 104 is interrupted in the manner previously described so that the label, withdrawn from the hopper 101 as set forth, is transferred from the plate 104 to the plate 138. The operation of the valves 139 as described above occurs in conjunction with the operation of the mechanism for transferring the labels from the plates 138 to the ends of the toilet roll packages as previously generally outlined, and the operation of this transfer mechanism will now be described.

Carried by the intermediate section 19 of the rotary head 4 and projecting transversely intermediate each adjoining pair of the forming heads 23 is a bracket 168, at the outer end of each of which a member 169 is journaled for rotation, see Fig. 14. This member telescopes with and is splined to a hollow member 171 which is also journaled in the bracket. A pin 172 carried by the member 171 extends into a bore 173 of the member 169, and a spring 174 on the pin tends to retain the members 169, 171 in their relatively extended positions as illustrated. The member 171 carries an arm 175, at the outer end of which is a perforated suction plate 176, this plate being connected with a source of suction as hereinafter described. The member 171 is moved axially with respect to the member 169 through the medium of a cam 177 mounted as shown in Fig. 2 upon the fixed structure of the machine, this cam being engaged by a bearing 178 at the rear end of the member 171. The members 169 and 171 are rocked through the medium of an arm 179 secured to the outer end of the member 169, see Figs. 14, 17 and 18, which arm has pivotally secured to its outer end a fitting 181 which receives a connecting rod 182, this rod having a sliding lost motion connection with the fitting 181 controlled by springs 183, 184 mounted on the rod 182, as shown in Figs. 17 and 18.

As shown in Figs. 2 and 4, the lower end of the rod 182 is connected to a rock shaft 185 journaled in the intermediate head section 19, and this shaft is connected through a link 186 to an arm 187 on a rock shaft 188 journaled in the head section 22, and having at its outer end an arm 189 which carries a roller 191, this roller traveling in a cam groove 192 in the cam plate 68. The limit of oscillation in both directions of

the members 169 and 171 is established by adjustable stop screws 190, which as shown in Fig. 17 cooperate with the arm 179.

The manner in which the suction plate 176 is attached to the arm 175 is shown in Figs. 15 and 16. The plate is secured against the face of a hollow flanged element 193, which element is slidably mounted in the end of the arm 175. Studs 194 secured in the element 193 extend through apertures in the arm 175 and carry springs 195 which hold the element 193 and the perforated plate 176 in an extended position of adjustment with respect to the arm 175. The interior chamber of the element 193 communicates through ports 196 with a chamber 197 in the end of the arm 175, and this chamber has a port 197a through which the chamber is connected to a duct 198 secured to the arm 175. The duct 198 is connected through a flexible tube 199 with a duct 201 secured to the bracket 168 and extending to a valve 202 mounted on the bracket. From the valve 202 a duct 203 extends to a port 204 in the hub of the intermediate head section 19, which port communicates with an annular chamber 205 in the inner surface of the hub. A port 206 in the shaft 18 establishes communication between the chamber 205 and a longitudinal passage 207 in the shaft, which passage extends to the end of the shaft and is connected through a duct 208 with a suitable source of suction. The valve 202 controls the connection between the suction plate 176 and the source of suction, and this valve is opened and closed through the medium of a lever 209 connected to the projecting end of the valve stem, see Figs. 1 and 2. At each end of the lever 209 is a roller 211 which is adapted for engagement with cams 212 mounted on the fixed structure of the machine, as shown in Fig. 1. Adjustable stops 213, 213 control the alternative positions of the lever 209, and a spring 214 secured to the lever 209 tends to hold the lever in either of the alternative positions while permitting rocking of the lever through the medium of the cam 212 from one position to the other.

The operation of this portion of the mechanism is as follows: The suction plate 176 in one extreme position of the rocking movement of the arm 175 occupies a position in which as shown at the right of Fig. 5 and in Fig. 23, it intersects the circular path of the suction plates 138 of the suction drum 128, so that at the point of intersection, the suction plate 176 lies in axial alignment with and in close proximity to the suction plate 138. At this point with the suction applied to the plate 176, the cam 158 acts upon the lever 151 to close the valve 139, whereby the label is transferred from the plate 138 of the drum 128 to the plate 176 of the arm 175. With the continued rotation of the head 4 and by operation of the cam 192, the arm 179 is now rocked into a position wherein the plate 176 with the label adhering thereto is brought into axial alignment with the associated toilet roll package. At this point, the cam 177 advances the arm 175 as previously described to press the label against the flat folded ends of the wrapper 3, as shown in Fig. 30a, the plunger 95 having been retracted to permit movement of the arm 175 into the aforesaid aligned position.

Intermediate the point where the label is transferred to the plate 176 and the subsequent bringing of the label into axial alignment with the toilet roll package, the gummed face of the label is wiped over a moisture roller 215 which wets the adhesive so that when the label is pressed against the ends of the roll it will adhere thereto. This

moistening device is illustrated in Figs. 1, 4 and 21. With reference to the latter figure, it will be noted that the drum 128 has keyed to the hub thereof a pulley 218 which through a belt 217 is operatively connected with a pulley 218 on a shaft 219, this shaft being journaled in a casing 221 supported on a bracket 222 forming a part of the fixed structure of the machine. The belt 217 is tensioned by a pulley 223, see Fig. 1, which as shown in Fig. 21 is resiliently pressed against the belt by a spring 224. The shaft 219 carries a bevel gear 225 which meshes with a bevel pinion 226 on a shaft 227 journaled in the casing 221, and this shaft carries a spur gear 228 which meshes with a spur gear 229 mounted on a shaft 231 also journaled in the casing 221 and paralleling the shaft 227. The gear 228 meshes with a gear 232, and the gear 229 with a gear 233, which gears are mounted on shafts 234 and 235 respectively journaled in the casing 221 and paralleling the shafts 227 and 231. The projecting ends of the shafts 227 and 231, see Fig. 1, carry rollers 236, 236 respectively which operate to pick up moisture from a receptacle 237, and these rollers contact respectively with the rollers 215 which are mounted on the shafts 234 and 235. The shafts 234 and 235 are journaled in brackets 238, which brackets in turn are journaled on the shafts 227 and 231 respectively, and the brackets 238 have a limited rocking movement and are normally retained resiliently in relatively extended positions and in the path of the suction plates 176 of the arms 175 by means of a spring (not shown). The rollers 215 pick up moisture from the rollers 236, which moisture is transferred to the gummed labels as previously set forth.

Subsequent to the pressing of the labels against the ends of the wrapped packages as previously described, the suction is cut off from the plates 176, thereby releasing the labels, and the arms 175 are withdrawn. The completed package is then discharged from the clamping devices to the chute 7, the arms 24 of the clamps being retracted as previously described by action of the cam 38 and as illustrated in Fig. 5.

It is believed that the operation of the machine will be readily understood from the foregoing description taken in conjunction with the diagram of Fig. 32, which shows graphically the movements of the various elements of the mechanism in relation to each other through a cyclic movement of the rotary head 4 of 360°.

I claim:

1. In a machine of the character set forth, the combination with roll-holding means, of mechanism operatively associated therewith and adapted to operate on the projecting ends of a wrapper embracing a roll supported in the holder to fold said projecting wrapper-ends simultaneously against the opposite end faces of the roll, said folding mechanism comprising means for temporarily retaining said folds in position, mechanism for applying labels adhesively to the folded wrapper ends, and power means for synchronously actuating said mechanisms.

2. In a machine of the character set forth, the combination with a conveyer structure comprising roll-holding means, of mechanism mounted in said structure in alignment with said holding means and adapted to operate on the projecting end of a wrapper embracing a roll supported in the holder to fold said projecting end against the face of the roll, mechanism also mounted in said structure for applying a label adhesively to the

folded wrapper, and power means for synchronously actuating said conveyer structure and mechanisms.

3. In a machine of the character set forth, the combination with a conveyer, of roll-holding means carried by said conveyer, mechanism movable with the conveyer and adapted to operate on the projecting end of a wrapper embracing a roll supported in said holder to fold said projecting end against the face of the roll, said mechanism comprising a folding-head positioned in alignment with said roll-holding means, and mechanism for advancing and retracting said head with respect to said holding means, elements on said head operative in the advanced position of the latter to force portions of said projecting wrapper-end against the face of the roll to thereby produce intermediate said portions a series of outstanding substantially radial tucks, means for jointly rotating said elements with respect to the roll to thereby lay said tucks flat against the face of the roll, means operative upon retraction of said head to hold said folds against the face of the roll, mechanism mounted on said rotary member for bringing a label into position at the end of said roll, means for simultaneously retracting said fold-holding means, and means for pressing said label against the folds and for adhesively securing said label to the latter to thereby permanently secure the folds in position.

4. In a machine of the character set forth, the combination with roll-holding means, of mechanism operatively associated therewith and adapted to operate on the projecting end of a wrapper embracing a roll supported in said holder to fold said projecting end against the face of the roll, said mechanism comprising a support structure, a plurality of shoes having substantially flat triangular working faces mounted in annular relatively spaced series in said structure and movable between retracted positions wherein said faces extend substantially parallel to the roll axis and advanced positions wherein said faces are substantially radial with respect to the roll axis, said shoes in the retracted position being adapted to embrace the end of the roll and the projecting end of the wrapper, and mechanism for advancing the shoes into the radial positions flatly against the end face of the roll with the apexes of said triangular faces adjoining the roll axis to thereby press relatively spaced segmental portions of the projecting wrapper-end against the said end face, said mechanism including means for initially resiliently engaging the basal portions of said triangular faces of said shoes with the substantially circular edge of the roll.

5. In a machine of the character set forth, the combination with roll-holding means, of mechanism operatively associated therewith and adapted to operate on the projecting end of a wrapper embracing a roll supported in said holder to fold said projecting end against the face of the roll, said mechanism comprising a support structure, a plurality of shoes having substantially flat triangular working faces mounted in annular relatively spaced series in said structure and movable between retracted positions wherein said faces extend substantially parallel to the roll axis; and advanced positions wherein said faces are substantially radial with respect to the roll axis, said shoes in the retracted position being adapted to embrace the end of the roll and the projecting end of the wrapper, and mechanism for advancing the shoes into the

radial positions flatly against the end face of the roll with the apexes of said triangular faces adjoining the roll axis to thereby press relatively spaced segmental portions of the projecting wrapper-end against the said end face, said mechanism including means for initially resiliently engaging the basal portions of the said triangular faces of said shoes with the substantially circular edge of the roll, and means for subsequently rotating said support structure.

6. In a machine of the character set forth, the combination with roll-holding means operatively associated therewith and adapted to operate on the projecting end of a wrapper embracing a roll supported in said holder to fold said projecting end against the face of the roll, said mechanism comprising a support structure, a plurality of elements individually pivotally mounted in said structure and arranged in annular series substantially concentric with said roll, a shoe having a substantially flat triangular working face movably mounted on each of said elements and forming with each other a relatively spaced annular series, means for actuating said elements to move the shoes between retracted positions wherein said faces extend substantially parallel to the roll axis and wherein the said series embraces the end of the roll and the projecting end of the wrapper, and advanced positions wherein said faces are substantially radial with respect to and against the end face of the roll, the apexes of said triangular faces adjoining the roll axis, and resilient means interposed between each of the shoes and its supporting element and operative to initially resiliently engage the basal portion of the said triangular face of the shoe with the substantially circular edge of the roll.

7. In a machine of the character set forth, the combination with roll-holding means, of mechanism operatively associated therewith and adapted to operate on the projecting end of a wrapper embracing a roll supported in said holder to fold said projecting wrapper-end against the face of the roll, said mechanism comprising a support structure, a plurality of elements individually pivotally mounted in said structure and arranged in annular series substantially concentric with said roll, a shoe having a substantially flat triangular working face movably mounted on each of said elements and forming a relatively spaced annular series, means for actuating said elements to move the shoes between retracted positions wherein said faces extend substantially parallel to the roll axis and wherein said series embraces the end of the roll and the projecting end of the wrapper, and advanced positions wherein said faces are substantially radial with respect to and against the end face of the roll, the apexes of said triangular faces adjoining the roll axis, resilient means interposed between each of the shoes and its supporting element and operative to initially resiliently engage the basal portion of the said triangular face of the shoe with the substantially circular edge of the roll, and means operative in the said retracted positions of the shoes for forcing the shoes toward their supporting elements against the pressure of said resilient means.

8. In a machine of the character set forth, the combination with roll-holding means, of mechanism operatively associated therewith and adapted to operate on the projecting end of a wrapper embracing a roll supported in said holder to fold said projecting wrapper end against the face of the roll, said mechanism comprising a relatively

fixed head, a cylindrical sleeve mounted for axial movement in said head, a plurality of segmental elements movably mounted in said sleeve in relatively spaced annular series, said elements being movable from normal retracted axially extended positions to advanced substantially radial positions, means for actuating said shoes including a driving pinion for each shoe, a rack operatively associated with each pinion and mounted in said sleeve for axial sliding movement, support means for said racks movable axially with respect to the sleeve, a spring interposed between the sleeve and said rack support means, mechanism for axially moving said support means, and means for limiting the axial movement of the sleeve in the head, said mechanism being effective through the spring to advance the sleeve in the head to the limit of its advance movement, and subsequently by compression of said spring to axially move the racks with respect to the sleeve to thereby actuate said segmental elements.

9. In a machine of the character set forth, the combination with roll-holding means, of mechanism operatively associated therewith and adapted to operate on the projecting end of a wrapper embracing a roll supported in said holding means to fold said projecting wrapper-end against the face of the roll, said mechanism comprising a relatively fixed head, a sleeve adapted for axial reciprocation within said head, segmental elements movable with the sleeve and movable on the sleeve from retracted axially extended positions to advanced substantially radial positions, a pinion for actuating each of said segmental elements, a rack slidable axially in the sleeve for actuating each of said pinions, means for preventing relative rotational movement between the racks and said sleeve, rack-supporting means axially movable with respect to the sleeve, a spring interposed between the sleeve and said rack-supporting means, mechanism for axially reciprocating said rack-supporting means, and means for limiting the axial movements in the head both of the sleeve and of said rack-supporting means.

10. In a machine of the character set forth, the combination with roll-holding means, of mechanism operatively associated therewith and adapted to operate on the projecting end of a wrapper embracing a roll supported in said holding means to fold said projecting wrapper-end against the face of the roll, said mechanism comprising a relatively fixed head, a sleeve adapted for axial reciprocation within said head, segmental elements movable with the sleeve and movable on the sleeve from retracted axially extended positions to advanced substantially radial positions, a pinion for actuating each of said segmental elements, a rack slidable axially in the sleeve for actuating each of said pinions, means for preventing relative rotational movement between the racks and said sleeve, rack-supporting means axially movable with respect to the sleeve, a spring interposed between the sleeve and said rack-supporting means, mechanism for axially reciprocating said rack-supporting means, means for limiting the axial movements in the head both of the sleeve and of said rack-supporting means, and mechanism for oscillating the sleeve in the head.

11. In a machine of the character set forth, the combination with roll-holding means, of mechanism operatively associated therewith and adapted to operate on the projecting end of a

wrapper embracing a roll supported in said holding means to fold said projecting wrapper-end against the face of the roll, said mechanism comprising a relatively fixed head, a sleeve adapted for axial reciprocation within said head, segmental elements movable with the sleeve and movable on the sleeve from retracted axially extended positions to advanced substantially radial positions, a pinion for actuating each of said segments, a rack slidable axially in the sleeve for actuating each of said pinions, means for preventing relative rotational movement between the racks and said sleeve, rack-supporting means axially movable with respect to the sleeve, a spring interposed between the sleeve and said rack-supporting means, mechanism for axially reciprocating said rack-supporting means, means for limiting the axial movements in the head both of the sleeve and of said rack-supporting means, mechanism for oscillating the sleeve in the head, a plunger slidably supported at the axis of said sleeve and projecting from the end of said head, mechanism for axially advancing said plunger in the head and with respect to said

sleeve, and a spring tending to retain said plunger in the retracted position.

12. In a machine of the character set forth, the combination with roll-holding means, of mechanism adapted to operate on the projecting ends of a wrapper embracing a roll supported in said holder to fold said projecting wrapper-ends against the faces of the roll, said mechanism comprising a folding head positioned at opposite sides of and in alignment with said roll-holding means, and mechanism for advancing and retracting said heads with respect to said holding means, elements on each of said heads operative in the advanced positions of the latter to force portions of said projecting wrapper-ends against the faces of the roll to thereby produce intermediate said portions a series of outstanding substantially radial tucks, means for jointly rotating said elements with respect to the roll to thereby lay said tucks flat against the faces of the roll, mechanism for applying and adhesively securing labels to the folded ends of the wrapper, and power means for synchronously actuating said mechanisms.

PHILIP D. PARSONS. 25
